ATTORNEY

UNITED STATES PATENT OFFICE.

ARTHUR ATWATER KENT, OF PHILADELPHIA, PENNSYLVANIA.

HORN.

1,222,107.

Specification of Letters Patent.

Patented Apr. 10, 1917.

Application filed June 17, 1911. Serial No. 633,651.

To all whom it may concern:

Be it known that I, ARTHUR ATWATER KENT, a citizen of the United States, and a resident of the city of Philadelphia and State of Pennsylvania, have invented certain new and useful Improvements in Horns, of which the following is a full, clear, and complete disclosure.

My invention relates to horns, and more particularly to such horns as are used in motor cars, boats, and similar vehicles, and in which the sound is produced by vibrating a diaphragm, the sound so produced being amplified and projected by a tapering horn, megaphone, or other suitable sound amplifying device.

My invention further relates to those horns of the class to which reference has above been made in which the diaphragm is set into vibration mechanically by a rotating wheel, cam, or disk having projections, undulations or corrugations arranged thereon and to be brought into successive rapid striking engagement with the diaphragm, the said cam, wheel or disk being actuated and rotated by an electric motor preferably contained within the casing in which the diaphragm is also mounted.

The object of my invention is to mount the motor of the horn within the casing and so disposed or positioned with respect to the casing and the diaphragm as to simplify the construction and to allow the motor to operate substantially directly upon the diaphragm with the fewest possible intermediate parts; to mount the motor so that the motor shaft may be used upon which to directly mount the diaphragm vibrating means and to support the said means in such a position as to permit or allow it to act directly upon the diaphragm; to mount the armature of the motor of the means for vibrating the diaphragm both on the same shaft; to provide means whereby the means for operating the diaphragm may be adjusted and brought into juxtaposition or operative engagement or relation to the diaphragm by merely moving or adjusting the motor shaft longitudinally; to locate the motor shaft adjusting means in a position where it is accessible and easily manipulated; to mount within the casing of the horn a motor in which the rotatable armature is not concentrically arranged with respect to the field of the motor so that the field windings may be placed, generally

speaking, on one side of a plane passing through the axis of the casing while the rotatable armature occupies a position on the other side of the said plane, thus providing ample and convenient space for the bearings, commutator and brushes and other parts of the motor; arranging the motor shaft so that it is in convenient operative relation to the diaphragm and may be adjusted without interference with the other parts of the motor; to arrange a motor of the type above described so that it occupies and fills substantially the entire cross sectional area of the casing; and to make the whole device simple, attractive, relatively inexpensive to manufacture, and serviceable.

Other objects of my invention will appear in the specification and claims below:

In the drawings forming a part of this specification in which the same reference characters are used throughout the various views to designate the same parts, Figure 1 is a transverse longitudinal section of a horn embodying my invention, and Fig. 2 is a rear elevational view of the same with the back cap or cover removed to show the manner in which the parts are disposed within the case.

In the embodiment of my invention illustrated in the accompanying drawing a preferably cylindrical casing 1 of sheet metal is provided at one end with a portion 2 slightly reduced in diameter, and with a closed end 3 preferably integral therewith. The opposite end of said casing, which is preferably closed by a cap 4 provided with a cylindrical flange 5, the outer diameter of which is the same as the interior diameter of that end of the casing 1. This cap is also preferably of sheet metal and is provided internally with a shoulder 6, forming a seat for the diaphragm. The front wall of said cap 4 is preferably provided with an offset 7, so that the front or forward wall of the said cap 4 projects outwardly from the end of the casing 1. Within said cap and resting with its extreme peripheral edge or face upon the seat 6 is the diaphragm 8 of preferably thin material. This diaphragm is retained in its position within the said cap 4 by a cap-shaped head 9, having a lateral extending circumferential flange 10, fitting within the interior of the flange 5 of the cap 4. The end of the flange 10 bears upon the extreme peripheral edge of the diaphragm 8, and is also preferably beveled at its inner

edge so that a comparatively narrow surface at the end of the flange 10 actually engages the diaphragm 8. The offset of the forward wall of the cap 4 thus provides a chamber 11 between the diaphragm and the cap and a chamber 12 is also provided by the cap-shaped head between the vertical wall thereof and the diaphragm.

The cap 4 is provided upon its front face 10 with a circular flange 13 to provide an opening 14 communicating with the chamber 11, and to form a support over which the projector or amplifier 15 is fitted and mounted.

The head 9 is preferably fitted within the cap 4 by a driving fit so that the two said parts are frictionally retained together and the diaphragm is rigidly mounted at its extreme peripheral faces between the two and the cap 4 is also fitted into the open end of the casing, one by a driving fit so that it is retained therein frictionally; that is to say, by reason of the friction between the two parts.

Within the casing 1 is mounted the actuating motor 16 which, as illustrated, is preferably of the type in which the armature 17 is mounted between two poles 18-18 on opposite sides thereof and which are energized by the field coil 19, between said poles 18. By this arrangement the coil 19 is located on one side of a plane passing through the longitudinal axis of the cylindrical casing while the armature 17 is substantially on the other side of said plane, while the poles 18-18 form a convenient frame for mounting for the motor within the case. The motor thus arranged occupies substantially the entire cross sectional area of that portion of the casing, filling it and making it rigid with respect thereto. This arrangement also makes the motor shaft 20 upon which the armature is mounted parallel to the axis of the casing and eccentric to the diaphragm, the purpose and utility of which will appear below.

The head 9 is provided with an opening in alignment with the motor shaft 20 within which to mount a journal 21 for said motor shaft. The rear wall 3 of the casing 1 provides a support upon which is secured a bracket 22 as by screws 23, within which is mounted the journal 24 for the other end of the motor shaft 20. Also upon the end 3 of the casing 2 is mounted the block 25 by which are carried the commutator brushes 26 which engage opposite sides of the commutator 27, it being understood that the parts are properly insulated in any well known and obvious manner.

Suitably secured to the forward end of the motor shaft 20 is a disk or wheel 28, the forward face of which near its periphery is provided with a series of projections or corrugations 29. The diameter of the said wheel or disk being such that the said corrugations 29 extend to and are in alignment

with the axis of the casing, or the center of the diaphragm; that is to say, the rotation of the wheel 28 brings the corrugations successively through the axis of the diaphragm; the diaphragm is provided at its center with a bushing 30 within which is secured a hardened stud 31 having a head 32 forming a projection of the diaphragm preferably in the form of a segment of a sphere. This head or projection 32 of the diaphragm extends into the path of the corrugations or projections on the face of the wheel or disk 28, and when the proper pressure is applied between the head 32 and the disk 28 the rotation of the disk will produce positive and rapid vibrations of the diaphragm of considerable amplitude. In other words, as the disk 28 is revolved the projections 29 on the disk will ride over the projection 32 of the diaphragm, and the elasticity of the diaphragm will cause the head to follow the undulations formed in the face of the disk 28. The faster the disk is revolved the more rapid will be the vibrations and the higher the pitch of the sound generated by the vibrations of the diaphragm.

To obtain the necessary and proper amount of pressure between the projection 32 of the diaphragm and the corrugated portion of the face of the disk or wheel 28 in engagement therewith, the shaft 20 may be adjusted longitudinally in its bearings 21 and 24 in any well known manner. In Fig. 1 I have illustrated one manner in which such an adjustment of the motor shaft 20 may be effected. The outer end of the journal box 24 is provided with screw threads and over the same is threaded a thrust bearing in the form of a cap 33 provided with a set screw 34. By turning the cap 33 after the set screw 34 has been loosened the shaft 20 will be pushed longitudinally in its bearings and adjusted to any predetermined or desired position, the armature 17 and commutator 27, and disk or wheel 28, being rigidly mounted on said shaft 20, are moved therewith. It will be thus seen that I have provided a simple way of bringing the disk or wheel 28 into operative relation with the projection 32 of the diaphragm. Inasmuch as the amount of movement which it is necessary to impart to the said shaft 20 longitudinally is relatively slight the operation or efficiency of the motor will not be affected thereby, and it is not necessary to carefully adjust the entire motor within the casing with respect to the diaphragm.

It will also be seen that I am enabled to mount the diaphragm engaging and operating means, viz., the corrugated wheel or disk, directly upon the motor shaft 20, and without any other intermediate device, directly vibrate the diaphragm therefrom or thereby.

Over the reduced end 2 of the casing I fit the rear cap or cover 35 so that it may be

fitted tightly thereover and frictionally retained thereon.

From the above it will also be apparent that I have provided a horn of the type above described in which the whole device is mounted within a casing symmetrically with the longitudinal axis of the same and preferably cylindrical, thus making a device which is easy to assemble, is attractive in appearance, and harmonizing in contour with the ordinary tapering projection or sound amplifier. By arranging the motor shaft substantially eccentric to the center of the diaphragm and the axis of the casing, a simple wheel or disk with projections upon its forward face may be mounted directly upon the shaft to form the diaphragm actuating or vibrating means.

While I have thus described one embodiment of my invention I do not wish to be construed to being limited to the same as various changes in shape, arrangement and disposition of the parts may be made so long as the structure so modified falls within the spirit and scope of the appended claims.

Having thus described my invention what I claim and desire to protect by Letters Patent of the United States is:

1. In a horn the combination of a casing, a motor having a field winding on one side and an armature on the other side of a plane passing through the longitudinal axis of said casing, a shaft on which said armature is mounted, the axis of said shaft being parallel to and out of alinement with the longitudinal axis of said casing, a disk provided with corrugations on its face and adjacent its periphery mounted on said shaft, and a diaphragm mounted in said casing and provided with a projection at its center extending into the rotative path of the corrugations on said disk.

2. In a horn the combination of a casing, a motor having a field winding substantially on one side, and an armature substantially on the other side of a plane passing through the longitudinal axis of said casing, a shaft on which said armature is mounted, the axis of said shaft being parallel and out of alinement with the longitudinal axis of said casing, a disk provided with corrugations on its face and mounted on said shaft, a diaphragm mounted in said casing and provided at its center with a projection extending into the path of the corrugations on said disk, and means to adjust said shaft longitudinally to bring said corrugations on said disk into proper operative relation to said projection on said diaphragm.

3. In a horn the combination of a casing substantially symmetrical in transverse section, a diaphragm, a cap fitting within one end of said casing and provided with a seat

for said diaphragm, a head fitted within said cap, and also provided with a seat for said diaphragm, said cap and said head engaging only the extreme peripheral faces of said diaphragm, and forming chambers on opposite sides of said diaphragm, an opening in the front of said cap, and a sound amplifier projecting from said opening.

4. In a horn the combination of a casing substantially symmetrical in transverse section, a diaphragm, a cap fitting within one end of said casing, and provided with a seat for said diaphragm, a head fitted within said cap and also provided with a seat for said diaphragm, said cap and said head engaging only the extreme peripheral faces of said diaphragm, and forming chambers on opposite sides of said diaphragm, an opening in the front of said cap, a sound amplifier projecting from said opening, a motor shaft in said casing, a journal in said head for said shaft, and means, mounted on said shaft and within the said chamber between said head and said diaphragm, to vibrate said diaphragm.

5. In a horn the combination of a cylindrical casing, a cap having a cylindrical flange and a shoulder to form a diaphragm seat, a diaphragm mounted on said seat with the extreme periphery of one of its faces in engagement with said seat, a head having a cylindrical flange forced within said flange on said cap, the end of said flange being narrow to form a seat for the opposite side of said diaphragm, said diaphragm being clamped between said cap and said head, and engaging said seats at the extreme peripheral portions of its opposite faces.

6. In a horn the combination of a casing substantially symmetrical in transverse section, a cap having a laterally extending flange conforming to the shape of the interior of the end of said casing, and with a shoulder, a diaphragm having its extreme peripheral face seated against said shoulder, a head having a laterally extending flange forced into said flange of said cap and with its end in engagement with the extreme peripheral portion of said diaphragm, said head being retained in said cap by the frictional engagement between the flange on said cap and the flange on said head and said cap being forced into the end of said casing, and retained therein by the frictional engagement between the exterior of said flange and the interior of said casing.

In witness whereof I have hereunto set my hand this twelfth day of June, 1911.

ARTHUR ATWATER KENT.
